US0D1111343S

(12) United States Design Patent (10) Patent No.: US D1,111,343 S
(45) Date of Patent: * Feb. 10, 2026

(54) MULE

(71) Applicant: Birkenstock IP GmbH, Linz am Rhein (DE)

(72) Inventor: Parthasarathhee Behura, Linz am Rhein (DE)

(73) Assignee: Birkenstock IP GmbH, Linz am Rhein (DE)

() Term: 15 Years

(21) Appl. No.: 35/522,910

(22) Filed: Oct. 10, 2024

(80) Hague Agreement Data

Int. Filing Date: Oct. 10, 2024

Int. Reg. No.: DM/241477

Int. Reg. Date: Oct. 10, 2024

Int. Reg. Pub. Date: Nov. 8, 2024

(30) Foreign Application Priority Data
